UNITED STATES PATENT OFFICE.

GEORGE VICTOR TOMLIN, OF CLEVELAND, OHIO, ASSIGNOR TO THE DAMASCUS BRAKE BEAM CO., OF CLEVELAND, OHIO, A CORPORATION OF OHIO.

BRAKE-BEAM FULCRUM.

1,145,527.

Specification of Letters Patent.

Patented July 6, 1915.

Application filed July 17, 1914. Serial No. 851,510.

To all whom it may concern:

Be it known that I, GEORGE VICTOR TOMLIN, a subject of the King of Great Britain, residing at Cleveland, in the county of Cuyahoga and State of Ohio, have invented certain new and useful Improvements in Brake-Beam Fulcrums, of which the following is a specification.

The object of my invention is to eliminate the tendency to split the fulcrum members apart by the brake beam member seated between them, by having the plane of connection between the members intersecting the plane of the tension member; and with these and other objects in view, my invention consists of the parts and combination of parts as will be hereinafter more fully set forth.

In the drawing Figure 1 is an elevation of a trussed brake beam showing one of my improved fulcrums or struts secured thereto; Figs. 2 and 3 are enlarged detail elevations of my improved fulcrum at right angles to each other, and Figs. 4 and 5 are enlarged detail elevations showing another embodiment of my improved fulcrum or strut.

The reference numeral 1 designates the compression member and 2 the tension member of the brake beam, to which is secured at each end a brake head 13 of approved construction. The strut or fulcrum is preferably a single forging having two members 3 and 4 bulged intermediate their ends for the passage of a brake lever which is pivoted therebetween on a bolt which passes through the bolt openings 5. Immediately below the bulged portions, the members 3 and 4 are brought together and secured by means of a rivet 6. The lower end portions of the members 3 and 4 are deflected at substantially right angles to the plane of connection between the members 3 and 4, and are formed to the configuration of the tension member 2 and constitute seats 7 and 8 for said tension member, the plane of connection between the members 3 and 4 intersecting the plane of the tension member, so that the tension member has no tendency whatever to split the fulcrum in the plane of connection of its members 3 and 4.

In order to rigidly secure the strut to the compression member 1, which in the present instance is shown as an angle bar, but might just as well be a channel between the two sides of which the head 11^a of the strut fits

snugly, a clip or brace 9^a is laid around the compression member, so that the latter is clamped between the clip and the head 11^a of the strut. This head is formed in the bend between the two members or legs 3 and 4, which are turned sharply inward without meeting to form a neck, so that a space, as at 12 is formed between the members 3 and 4. A bolt 10^a is drawn through the ears of the clip 9^a and the spaced portion 13 of the members 3 and 4. This spacing 12 will make the joint more secure than if the head and neck were solid, as, on account of the flexibility of the head and neck the bolt and nut 10^a may be drawn up tighter. 70

It will be seen from the construction shown in Figs. 1, 2 and 3, that by reason of the fact that the plane of connection between the members 3 and 4 intersects the plane of the tension member, no work is imposed upon the rivet 6 other than to normally hold the members 3 and 4 together, the work imposed on the fulcrum by the tension member being carried entirely by the tension member by reason of the fact 75 that the plane of connection between the two members intersects the plane of the tension member. 80

In Figs. 4 and 5, I have shown another embodiment of my invention wherein the ends 9 and 10 of the fulcrum members 3^a and 4^a are deflected toward each other and the lower end portions of the members 3^a, 4^a are each provided with an opening 11 constituting the seat for the tension member 2. As in the other constructions above described, the plane of connection between the members of the fulcrum intersects the plane of the tension member, thus eliminating all tendency of the tension member 90 to split the fulcrum. 95

I claim:

1. A fulcrum or strut for brake beams comprising a single forging having two members integral at one end, and having a tension member bearing at their other ends and connected together near the tension member bearing and having the plane of connection intersecting the plane of the tension member, said tension member bearings being formed by bending the end of the forging transversely to said plane of connection. 100
2. A strut for brake beams comprising a double bent strap, the bend forming an 110

abutment head against the compression member, a neck under said head formed by the spaced sides of the strap, and means including a tension bolt through said neck 5 for securing the strut to the compression member.

3. A strut for brake beams comprising a double bent strap, the bend forming an abutment head against the compression member, 10 a neck under said head formed by the spaced sides of the strap, and means including a tension bolt for securing the strut to the compression member, and a clip embracing the compression member and said 15 neck, said tension bolt being drawn through said neck and the ends of the clip.

4. A strut for brake beams comprising a double bent strap, the bend forming an abutment head against the compression member, 20 a neck under said head formed by the spaced sides of the strap, and means including a tension bolt for securing the strut to the compression member, and a clip embracing the compression member and said 25 neck, said tension bolt being drawn through said neck and the ends of the clip, thereby securely clamping the compression member between said head and said clip.

5. A strut for brake beams comprising a

double bent strap, the bend forming an 30 abutment head between the sides of the compression member, a neck under said head formed by the spaced sides of the strap, and means including a tension bolt for securing the strut to the compression member, and a 35 clip embracing the compression member and said neck, said tension bolt being drawn through said neck and the ends of the clip, thereby securely clamping the compression member between said head and said clip. 40

6. A strut for brake beams comprising a double bent strap, the bend forming an abutment head against the compression member, a neck under said head formed by the spaced 45 sides of the strap, and means including a tension bolt for securing the strut to the compression member, the free ends of said strap abutting against each other and being bent transversely to fit snugly against the tension member. 50

The foregoing specification signed at Cleveland, Ohio, this 20th day of March, 1914.

GEORGE VICTOR TOMLIN.
